UNITED STATES PATENT OFFICE.

WILLIAM G. RICHESON, OF BOSTON, ASSIGNOR OF ONE-HALF HIS RIGHT
TO JOHN F. RAMSDELL, OF QUINCY, MASSACHUSETTS.

IMPROVEMENT IN CAMP-BEDS.

Specification forming part of Letters Patent No. **210,148**, dated November 19, 1878; application filed May 6, 1878.

To all whom it may concern,

Be it known that I, WILLIAM G. RICHARDSON, of Boston, in the State of Massachusetts, have invented a new and useful Improvement in Camp-Beds, of which the following

The object of this portable folding camp is stiff and rigid, and used, and yet which attached to the legs or

The nature of the information in detail is described below.

In the drawings, in reference indicate like respective view of my position for use. Fig. 3 is the same. Fig. 3 is line x , Fig. 2.

drawing, their upper
pieces from their upper
ends bent into horizon
ing the grooved port
which are secured to the
portion of a floor. *b*
ed between the end
d are legs, two be
piece *c* by means of
fold inwardly when
a leg *d* is provided
oint, to prevent it
iron rods, four in
ape shown in the
entering the cross
es, and their lower
ositions and enter
f' of the plates *f*,
or *a*.

To put up the bed, their positions in the grooves f' of the planks d as far apart as d'' will prevent them slipping out of position. Of course the secured in the proper place the rods e in pieces c and in the f ; then spread the sible, and the spurs slipping out of pos- f must be firmly sions first.

To take down the b
rst fold in the legs

d, as seen in broken lines, Fig. 2; then remove the rods *e*, and the bed may be folded or rolled up.

No braces are needed for the legs, as the rods *e* hold the bed in the firmest and stiffest manner. No racking from side to side is possible, and the rods entering the upper sides of the cross-pieces *c* hold it tightly and prevent the hinges from being strained.

The bed is highly adapted to camp-meeting use, and can be put up on the bare ground, if desired, by making the plates *f* of the proper size and shape.

As the legs and cross-pieces pitch or cant toward the center of the bed instead of being vertically placed, the weight of the occupant of the bed does not strain them, but only serves to stiffen them and drive them firmly into the floor.

The plates f are so placed that the grooves f' are at an angle with the cross-pieces c , and the rods e are inserted into the ends of the grooves farthest from the cross-pieces, so that there is no danger of the rods drawing out from the grooves.

Having thus fully described my invention, what I claim, and desire to secure by Letters Patent, is—

1. The combination of the cross-pieces *c*, bent rods *e*, and plates *f*, provided with the grooves *f'*, all arranged substantially as and for the purpose herein set forth.

2. The herein-described camp-bed, consisting of the cross-pieces *c*, canvas *b*, hinged legs *d*, provided with spurs *d''*, rods *e*, and grooved plates *f f'*, all substantially as and for the purposes above specified.

WILLIAM G. RICHARDSON.
